UNITED STATES PATENT OFFICE.

JOHN GOOD, OF BROOKLYN, NEW YORK, ASSIGNOR TO GOOD INVENTIONS CO., OF BROOKLYN, NEW YORK, A CORPORATION OF NEW YORK.

CARBURETING APPARATUS.

1,405,777.

Specification of Letters Patent. Patented Feb. 7, 1922.

Application filed April 27, 1916. Serial No. 93,883.

To all whom it may concern:

Be it known that I, JOHN GOOD, a citizen of the United States, residing at Brooklyn, in the county of Kings and State of New York, have invented the following-described Improvements in Carbureting Apparatus.

The improvements concern the structure, functional relation of parts, and mode of operation of suction-operated charge-forming devices for internal combustion engines, being more particularly an improved form of apparatus utilizing the principles of fuel and air measurement set forth and claimed in my prior application, Serial No. 5850, filed February 3, 1915, and comprehending also certain improvements upon the invention of said application and also certain independent features, the general object being a carburetor useful for gasoline and volatile fuels but especially adapted for heavy oils like the fuel oil of commerce, kerosene, etc., and also adapted to maintain constant or predetermined proper proportions of the fuel charge throughout a very wide range of engine operation and independent of the vaporization instrumentalities that may be employed, and further to simplify the proportioning means and avoid plural adjustments, or the need for skilled attention when in use, and also other objects.

In the drawings,

Fig. 1 is a generally longitudinal section;

Fig. 2 is a top plan view, with parts removed;

Fig. 3 an elevation partly in longitudinal section, on line III—III of Fig. 2;

Fig. 4 is a partial section on line IV—IV, Fig. 2;

Figs. 5 and 6 are modifications; and

Figs. 7 and 8 are further modifications.

Referring to Fig. 1, the apparatus there shown comprises a main casing 40, opening to atmosphere at its lower end and adapted for connection at its upper end to a tube section or passage 1 forming therewith the suction-intake for the engine. The said tube section, which may be merely a portion of the ordinary manifold pipe, constitutes the mixing chamber of the carbureting apparatus, that is to say, a space in which the air component of the charge is sprayed with the liquid component and in which the latter may also be vaporized by heat, both components having been previously measured in correct proportions for combustion. In Fig-

ures 1 to 4, and for a purpose presently explained, the mixing chamber is formed by a Venturi tube, and the liquid fuel is sprayed therein from a spray-nozzle 2 disposed at or near the throat of the venturi and the heat 60 is applied externally to the chamber by enclosing it in a box diagrammatically shown at 3 interposed either in the water-jacket circulation (for lighter fuels) or in the exhaust gas passage (for heavier fuels such as kerosene). When the chamber is provided with a Venturi tube, which is preferred, the air flow through it produces a marked reduction of pressure at the throat which is useful to cause or promote the discharge of liquid 70 from the nozzle 2 and its supply pipe 4, and for other purposes, but further according to this invention the venturi shown is representative of means employed for creating and maintaining a low pressure at the said 75 nozzle, regardless of whether the means is dependent on the velocity or amount of air flow, and the invention is not limited thereto to keep the pressure in the mixing space low enough to insure vigorous liquid discharge, 80 at all times, from idling to full load, and during abrupt changes of throttle adjustment. The liquid fuel may also be heated, prior to its introduction to the mixing chamber, in which case the liquid pipe 4 may be 85 housed within the heater for any necessary part of its length, as indicated, for example, by the coil 4^a, and such heating may be sufficient for vaporization, depending on the fuel, without heating the mixing chamber. 90

The air component of the charge flows to the mixing chamber through the main air passage in the casing 40 which is quite separate from the liquid passage 4, and carries pure air only, the rate of flow being as 95 determined by the throttle 5 which may be placed at any point in the intake, but the throttle is preferably located just in advance of the mixing chamber so that the latter may profit to the greatest extent by the suction vacuum of the engine. The entrance to the main air passage contains and is adapted to be closed by a check valve body 6 arranged to be moved or lifted by the air flow. This body is mounted on a staff 7 100 guided at the lower end in the frame or housing of a dash-pot 8 and at its upper end in a bushed hole in the wall of the main air-passage. The body itself is oval or stream line in shape having no 110

abrupt corners and is adapted to seat at its widest part upon or against the wall of the air inlet which wall is provided by an inserted piece or bushing 9 threaded with fine thread in the entrance of the casing and hence adjustable therein. Its inner surface is curved with a special curvature which controls the elevation to which the air moves or lifts the control body 6, as will be referred to later on. In the present case the entering air lifts the control body and its attached parts against the action of their gravity only and thereby there is established in the casing immediately above said body, a condition of pressure which is less than atmosphere, assuming atmosphere to surround the entrance end of the casing, and such pressure is constant for all values or volume of steady air flow through the entrance. As will presently appear, the said body might also be seated by the action of a spring, if desired, in which case the elevation assumed under a given air flow would be correspondingly modified and might also call for a corresponding modification of the curvature of the inner wall of the bushing 9 just referred to and as will be apparent further on. The condition of pressure determined in the air passage by the weight or seating tendency of the valve body 6, the same being constant in the present case, serves to induce the flow of liquid fuel from the constant-level float chamber 10 through a metering means and into a space where it may be transferred into the pipe 4. For this purpose the air passage through the main casing above the entrance is formed by the interior horn 11, and the space 13 in the casing outside the horn being a substantially dead space in communication with the pressure condition in the air passage through the annular gap 12, forms an enclosure for the flow-controlling agencies and connections, which latter are thus disposed out of the air flow and hence where they do not obstruct it.

The outlet of the casing air passage 11 to the mixing chamber is also controlled by a check valve member 14, which is also in the present case seated solely by its own gravity, like the body 6, and when seated forms a substantially complete closure to the suction intake, being adapted to be lifted by the air however, and to such extent as the volume flowing may lift it. This check valve member 14 is carried on a stem 15 guided in the casing and retarded in its action by a liquid dash-pot 16, the ported plunger of which is provided with a ball check therein so that the valve will rise relatively sluggishly and close quickly. Immediately above its seat the valve passage is enlarged to an ample cross-sectional area to avoid undue restriction of the flow but the pressure in the space beyond the valve is thereby reduced

more or less and in accordance with the seating tendency acting on the valve, so that there is thus established in the intake a series of pressure regions of successively lower pressure. The first is between the two check valve members and determined by the weight of the valve 6 and the second is on the engine side of the valve 14 and determined by its weight; depending upon its location, the throttle may establish another, which in the present case would succeed that of the valve 14, and the throat of the venturi, when used, establishes still another, but the throttle creates a depression behind it only when it is partially closed, and the venturi does so only in proportion to the flow velocity through it, and therefore both these elements, throttle and venturi, may be regarded as cumulative pressure reducing means supplementing the constant minimum pressure difference defined by the valve body 14, which latter is effective regardless of throttle position or air flow. Two principal regions of successively lower pressure are thus established by the two successively arranged check-valve bodies 6 and 14, and the pressure difference thereby maintained serves to assure vigorous movement of the liquid component of the charge and effective spraying in the mixing space, such difference being in no case less than a certain predetermined minimum represented by the gravity or seating tendency of the valve body 14.

Referring now to the liquid fuel supply, the float chamber 10 is conveniently mounted on or formed as a part of the main casing 40, and thus partakes of the uniform temperature of that apparatus. It is supplied with liquid fuel through a pipe connection 17, and kept at a substantially constant level by the usual float-controlled valve, as indicated, or otherwise. The upper end of the longitudinally moving staff 7, which projects into the space 13 carries rigid thereon a cross-arm 18 forming the operating connection to a metering pin 19, the latter being mounted in a bushing (Fig. 4) with its lower end protruding into an orifice 20, which latter will be seen to be the outlet from the liquid fuel chamber. The connection of the cross-arm to the metering pin is by means of a hole in the arm which is wider than the pin itself and is hence subject to lost motion, but the pin is held in normal relation to the arm by a spring so that the pin and staff move properly together and neither can be the cause of the others sticking in its bearings. The pin and body thus move together and accurately according to the position imparted to the control body 6 by the inflowing air. As shown in Fig. 4 the metering orifice 20 controls the liquid flowing from the float chamber through the passage 21 and permits it to pass the orifice at such rate as deter-

mined by the extent of protrusion of the tapered end of the metering pin 19 therein. From this metering point the fuel passes first laterally through the bore 22 and then upwardly through the bore 23 and again laterally through the bore 24 and thence downwardly into a small chamber 25. This chamber 25 is in communication with the pressure space 13, or is a part of said space out of the 10 air flow, but is subject to the pressure determined by the body 6, and in consequence, the liquid is caused to move from the float-chamber into the small chamber 25 as the result of the pressure difference existing between the 15 said pressure chamber 13 and whatever pressure may be acting upon the surface of the liquid in the float chamber. That pressure may be assumed to be atmosphere in the present case, although it might be otherwise 20 and the liquid thus moves to the chamber 25 under a substantially constant head from the liquid chamber, constant, because the body 6 is gravity-seated in the present case. The chamber 25, has a funnel-shaped bot- 25 tom forming the entrance end of the fuel pipe 4 above referred to and into which the measured liquid is transferred and wherein it passes, together with a slight amount of air from the transfer-chamber 25, to the 30 mixing chamber 1 for mixture or vaporization with the main body of air. As before stated the flow through the transfer pipe 4 results from the pressure difference always maintained between its receiving and spray 35 nozzle ends.

Constant proportions of fuel and air are maintained by the correlation established between the elevation assumed by the control body 6 and the position of the tapered 40 metering pin 19, in the metering orifice, as will now be evident. Such correlation is made with reference to the known variations in the characteristics of the flow of liquid from small orifices or nozzles and in the 45 present case is expressed in the curvature of the seat wall 9 of the body 6. The taper of the metering pin 19 is straight or conical and the seat wall on the part 9 is so curved as to define the proper elevation of the body 50 and corresponding position of said pin for all values of air flow, so that the rate of liquid flow bears at all times a constant ratio thereto. The proper curvature for this purpose can be plotted by reference to the 55 known law of liquid flow and the taper of the metering pin, or it can be established experimentally with a fair degree of accuracy by selecting proper diameters for the maximum, minimum, and several intermediate 60 positions of the control body. When the curvature has been established variation in the richness of the mixture may then be accomplished by simply screwing the seat part 9 inwardly or outwardly in the main casing, 65 which will not disturb the relationship of the

rates. The spring detent 26 serves to hold any such adjustment. However, it is manifestly also within the invention to form the special compensating curvature in the taper of the metering pin itself, as done in certain 70 known metering-pin carburetors, and in such case the curvature of the seat wall 9 may be such as to give a constant increment of elevation for equal increments of air flow, or otherwise. 75

It will be observed that change of the position of throttle 5 through its control of the intake, changes the elevation of the control body and correspondingly adjusts the liquid delivery through the transfer to the 80 mixing chamber. When the throttle 5 is closed tight or is so adjusted that the valve 14 remains seated, the body 6 is then lifted from its seat only to such extent as will satisfy the suction pull exerted from the 85 mixing chamber through the transfer pipe 4, and at such elevation establishes the proper rate of liquid supply to keep the engine turning over when under slight or no load, that is to say, when idling. The air 90 component of the charge in this case is constituted by that air which is drawn through the transfer pipe together with the liquid, and the capacity of the transfer pipe is determined with this object in view, so that 95 proper idling mixture will pass to the engine when the air throttle 5 is closed, or nearly closed. It is preferred, however, that the transfer pipe be made of larger capacity than necessary merely for the idling condition and to restrict it to the requirements of idling by the use of a valve or throttle therein, such as represented by 27. Thereby the same apparatus is adapted to serve a wide 100 variety of sizes of engines. When this liquid throttle is set to an intermediate position, the flow capacity of the transfer pipe is then suitable for transferring liquid and air in the proper amount for idling. Adjustment of the throttle 27 in the direction 105 to close the transfer pipe completely, as indicated in Fig. 1, will of course stop the engine by shutting off the fuel, and in the other direction (to the left in Fig. 1) enlarges the capacity for flow so that the pipe 110 may then transfer liquid in any amount required. The transfer throttle 27 is shown in Fig. 1 as geared with the air throttle 5 to assume automatically the proper position and so that from a single lever or control 115 pedal, the fuel can be controlled to bring the engine from full speed and maximum load, through the idling condition, to stop. The drawings illustrate an example of a form of such gearing, the rod 28 being assumed 120 to extend to the pedal or throttle lever. The position indicated is that of full closure of both throttles. Moving the rod 28 to the left allows the liquid throttle to open under 125 the influence of its spring, to its idling posi- 130

tion, while the throttle 5 remains closed, by virtue of the slot in the rod. Continued movement in the same direction allows the liquid throttle to open further and opens the 5 air throttle to the extent desired against the tension of its closing spring. Obviously various other forms of linkage or gearing can be substituted to produce the same mechanical effect.

- 10 In order to compensate for leakage in the engine around the pistons or in the engine valves or elsewhere, my invention includes a by-pass from the liquid fuel chamber around the metering pin to the transfer chamber 15 25, and thence to the mixing chamber. This by-pass is constituted in the present case, by the pipe 30, connected at its opposite ends with the liquid passages 24 and 21, respectively, and subject to accurate control by a 20 fine needle valve 31. When the engine is new this valve is closed but as leakage develops from engine wear, it is opened slightly to admit some fuel directly to the chamber at constant rate sufficient to satisfy 25 the substantially constant leakage inflow of air, and it may also be used when starting.

The pressure space 13 which contains the cross-arm 18 and metering pin connections, is formed in part by a bonnet 32 secured to 30 the upper face of the main casing 40, as indicated in the drawings, and so as to be removable to expose and permit removal of the metering pin 19 whenever required. The restricted metering orifice 20 is also 35 removable, being formed in a bushing threaded into the casing 40 from below and removable for inspection or cleansing by first removing the plug 33 and then unscrewing the bushing from its seat. The position of 40 the metering pin at one side of the control body allows either of these operations to be accomplished readily and without disturbing the adjustment of fuel and air proportions.

- 45 In addition to its function of maintaining the suitable pressure depression at the spray nozzle of the transfer pipe, the check valve member 14 being relatively sluggish in its opening movement by reason of its dash-pot 50 and being interposed in the main air-flow, serves a further useful purpose, not merely supplemental to its primary purpose but also independently useful in other relations and is so claimed herein. Its relatively slow 55 opening motion suppresses sharp fluctuations of pressure, such as might otherwise occur on sudden changes of operating conditions, as, for example, when the throttle is suddenly changed and the control body is 60 finding a new elevation. On such occasions the liquid supply tends to become irregular or erratic as the result of the abnormal motion and pressure conditions momentarily existing in the intake passage, and the 65 smoothing-out effect of the valve body 14

effectively counteracts and suppresses that tendency and also smooths out the pulsations that would otherwise be transmitted to the liquid outlet under slow speed and wide-open throttle conditions.

The apparatus shown in Figs. 1 to 4, assumes the liquid transfer pipe and the mixing chamber to be both heated by the engine exhaust gases which pass through the stove or passage 3. It will be evident, however, that the invention is not limited to such an arrangement; by way of a single example the liquid fuel pipe and the air passage may be so heated if desired (Fig. 5). Such separate heating can be done without disturbing the constancy of the fuel and air proportions and without fouling any of the interior ducts or surfaces, because the thermal expansion resulting from the heat occurs after measurement and while the fuel is separated from the main body of air, and further because the heat applied is sufficiently isolated from the point of fuel measurement that it cannot affect the rate of flow of the liquid by reducing or changing its viscosity, or cook or carbonize the oil in the metering orifice, which of course would tend to clog it or reduce its capacity. These are advantages of the present invention not possible in other carbureting apparatus where the heat is applied to the air prior to measurement or at the place of measurement. Moderate heating of the air prior to its measurement is not harmful provided the temperature is not sufficient to injure or break down the oil and provided also that the thermal expansion is not allowed to disturb the proportions, and the air might be preliminarily warmed in apparatus of this invention on these conditions, 100 but any such permissible moderate temperature is not sufficient to vaporize heavy gasoline or kerosene properly, in consequence of which it is preferred to apply all the heat after measurement, as above explained. 110 Fig. 5 illustrates the arrangement of the apparatus when the air is heated. In this figure the air outlet from the proportioning or measuring means already described, is connected to an air heater 35, so that the air 115 which has passed the check valve bodies 6 and 14 and there served to measure the fuel, will circulate through the said heater and enter the mixing chamber with the desired temperature. The transfer pipe 4 is led to 120 the mixing chamber through the same heater, so that the fuel will also be heated as it issues from the spray nozzle 2. Heating of the fuel is not necessary for normal running if the air has the proper temperature, but in cases where the air throttle 5 is completely closed when the engine is idling, some heating is necessary in order to continue vaporization of heavy oil under that condition. The air heater is provided with 125 130

inlet and outlet connections for the exhaust, to serve as the source of heat but any other source could be used and any type of heater. The mixing chamber is shown in this case 5 as consisting merely of a short section of the manifold of the engine and the air throttle as located between it and the proportioning means, but as already pointed out these are matters subject to variation. The air throttle 10 can be placed on the engine side of the mixing chamber, or at the inlet to the proportioning means, provided only that the pressure differences between the ends of the transfer pipe and between the float chamber 15 and the transfer chamber be kept constant or in proper relation to maintain the desired flow. The modified form of Fig. 6 illustrates the employment of the check valve body 14 as the main air throttle. The 20 bell crank lever 14^a fulcrumed in the casing wall engages the flattened top of the valve to close it, or to limit its opening movement, but not to open it so that the rate of air flow and the operation of the engine are thus 25 controlled without interference with the other functions of the valve 14.

Figs. 7 and 8 represent in transverse and longitudinal sections, respectively, the relation of the present invention to a further type 30 of vaporizer constituting the subject of a separate application for patent. In this type the air emerging from the check valve 14 and the air emerging from the check valve 14 and the throttle 5 passes into a downtake pipe 36, and discharges directly against the bowl-shaped floor 37 of a chamber 38, which latter is of relatively large proportions, as will be observed, and is in immediate connection with the engine through the inlet ports 39. The floor 37 is subjected to heat on its under 40 side in the present case by directing the exhaust from the engine directly against it. For this purpose the several exhaust ports 41 discharge into a manifold 42 and the latter discharges through an upturned spout 43 directly against the under side of the depressed floor, escaping thence through the outlet 44. The depressed floor 37 is thus 45 kept at substantially the temperature of the engine exhaust. The transfer pipe 4, supplied with liquid fuel by the mechanism 50 above described, is in this case looped through the exhaust gas passage beneath the floor 37 and then led through the floor and into the air flow in the downtake 36, with its nozzle 2 centralized therein, as shown in the 55 drawings. The air pipe and the liquid nozzle thus both discharge centrally and directly against the exhaust-heated wall or floor of a chamber of relatively large capacity and 60 which is intended to be placed close to the engine cylinders and in direct communication therewith. As shown in Fig. 8, the said chamber is bolted directly to the side of the cylinder head, so that the air and fuel previously measured may pass directly to their

place of combustion immediately on being brought into contact with the vaporizing surface and each other. This vaporizing apparatus in conjunction with the measurement and separate conduction of the liquid fuel 70 and air as above described, constitutes a most effective, cleanly and simple means for utilizing kerosene fuel in combustion engines without producing high resultant temperatures in the combustible mixture. Sufficient heat is 75 normally derived through the exhaust-heated floor 37, but the air can be additionally heated, as in the case of Fig. 5 if desired, and the oil can also be heated, as in fact illustrated in Figs. 7 and 8, and wherever the adjustment 80 for idling involves a complete closure of the air passage between the check valve body 6 and the engine, some heat is desirably applied either to the transfer pipe or the vaporizer chamber, as already explained. It 85 will be understood that the upper part of the casing 40 of the fuel and air-proportioning means will be variously shaped for compact connection to the pipe fittings of the particular system in which the invention is embodied. It will be also understood that while I have described and illustrated the invention as organized for supplying fuel charge to combustion engines it is likewise serviceable for supplying carbureted mixture to 90 combustion apparatus of any kind.

I claim:

1. Carbureting apparatus comprising a suction intake having a throttle, a liquid fuel supply chamber having its outlet subject to less than atmospheric pressure within the receiving end of said intake, and a transfer pipe to conduct liquid from said outlet to a space in the intake near the engine, in combination with means independent of the 100 throttle for maintaining a predetermined minimum pressure difference between the receiving and discharge ends of said transfer pipe.

2. Carbureting apparatus comprising a 110 suction intake including a mixing space in which liquid fuel is sprayed into air and provided with a check-valve member for maintaining in said space a region of relatively low pressure and means for maintaining a region of relatively higher pressure in the intake in advance of said space, both pressures being less than atmosphere, and a throttle controlling the flow through said intake, in combination with a liquid fuel supply subject to the higher pressure in said intake and a transfer pipe conducting liquid from said supply to the mixing space.

3. Carbureting apparatus comprising a 125 suction intake provided with a throttle and with means for maintaining regions of successively lower pressure therein less than atmosphere and including a mixing chamber in a region of lower pressure, in combination with a liquid fuel transfer pipe leading from 130

- 5 a higher pressure region of the intake to the mixing chamber and having a nozzle orifice adapted to spray liquid therein, and an air-actuated metering means controlling the delivery of liquid into said transfer pipe.
- 6 4. Carbureting apparatus comprising a suction intake having a throttle and two air-operated pressure-determining valve-bodies disposed in series relation in said intake, one 10 of said bodies serving to control the rate of liquid delivery and a transfer pipe conducting the delivered liquid to the region of pressure in said intake determined by the second of said bodies.
- 15 5. Carbureting apparatus comprising an intake passage and successively arranged air-sustained bodies therein, a liquid receiving chamber having communication with the intake between said bodies, means whereby 20 the position of one of said bodies controls the rate of flow of liquid to said chamber and a liquid transfer pipe connecting said chamber with the intake on the engine side of the other of said bodies.
- 25 6. Carbureting apparatus provided with an air entrance and a mixing chamber, an air passage conducting air from said air entrance to said chamber, a liquid passage adapted to conduct all of the fuel and also to 30 conduct some air from within said air passage to said chamber, and means within said air passage and sustained by the flow of air through said entrance for controlling the rate of fuel supply to the liquid passage.
- 35 7. In carbureting apparatus, a mixing space for air and liquid fuel, a liquid fuel chamber, the outlet whereof is controlled by the relation of a straight-tapered metering member to a liquid outlet member, an air-sustained body of stream-line form 40 connected to operate one of said members to vary the cross-sectional area of the liquid outlet, an entrance passage through which all the air component of the charge moves 45 to the mixing space, said entrance being provided with a seat portion for said body having a curvature plotted to control said area to maintain a predetermined rate of liquid flow, and a transfer pipe conducting 50 liquid so measured to the mixing space, having its receiving end subject to the pressure determined by said air-sustained body.
- 55 8. Carbureting apparatus comprising a main casing having an inlet adapted to reduce the pressure of air passing therethrough and having a check valved outlet and a mixing chamber connected with said outlet beyond the check valve member thereof, in combination with a liquid transfer 60 chamber subject to the pressure between said inlet and check-valve and a liquid chamber having a liquid outlet delivering into said transfer chamber and a transfer pipe collecting the delivered liquid and conducting the same with some air from said 65 transfer chamber to the said mixing chamber.
9. Carbureting apparatus comprising a main casing having a check-valved inlet and a check-valved outlet and a mixing chamber connected with said outlet beyond the check valve member thereof, in combination with a liquid transfer chamber subject to the pressure between said check-valves, a liquid supply to said chamber controlled by the inlet check-valve member and a transfer pipe from said transfer chamber to the said mixing chamber. 70
10. Means for supplying liquid fuel charges to internal combustion engines, comprising a space in which the liquid fuel is sprayed with air, an air intake leading to such space, an air inlet to said intake, and an air throttle between said space and inlet, in combination with a liquid fuel supply receptacle having a discharge opening subject to the pressure in said intake adapted to deliver liquid in a predetermined ratio to the air entering the aforesaid inlet, a liquid transfer pipe conducting all the so discharged liquid to the said mixing space, mechanical means independent of the throttle for permanently maintaining a pressure actuated liquid flow through said transfer pipe for all throttle adjustments, and means 80 for heating the transfer pipe. 85
11. In carbureting apparatus, the combination of an air pipe conducting air only, a liquid pipe conducting the whole fuel component of the carbureted mixture, a mixing space in which the latter pipe delivers to the former, a valve member in the air pipe operative to maintain a normal pressure difference between the ends of the liquid pipe and a retarding means for said member adapting it to maintain said pressure difference on sudden fluctuations of the air flow. 90 100
12. Carbureting apparatus, comprising in combination with an intake passage having two independent check valve members opened by air flow therethrough, a transfer pipe receiving liquid fuel from the space between said members and conducting the same into the air flow beyond the second valve member and mechanically correlated throttles for said transfer pipe and the air flow respectively. 105 110
13. Carbureting apparatus comprising an air intake provided with means whereby spaces of successively lower pressure are maintained therein the lowest pressure being maintained by a check valve member intercepting the air flow, a transfer pipe conducting liquid fuel from the space of higher pressure around said check valve member to the space of lower pressure, a throttle to control the air flow, a throttle in said transfer pipe and a mechanical operating connection between said throttles. 115 120
14. Carbureting apparatus comprising in 125

combination with a suction intake, two independent dash-pot retarded check valve members disposed in successive positions within said intake, said apparatus being 5 provided with a second passage terminating at opposite sides of that one of said two check valve members which is nearer the en-

gine, and liquid fuel controlling means within said intake operated by the movement of one of said members delivering fuel 10 to said second passage.

In testimony whereof, I have signed this specification.

JOHN GOOD.
